IVER JOHNSON, OF BURNABY, BRITISH COLUMBIA, CANADA

DIRECTION INDICATOR

Application filed February 8, 1931. Serial No. 514,392.

My invention relates to improvements in direction indicators for motor cars and the like.

The objects of the invention are to produce a device capable of displaying a signal in a substantially similar manner to the hand signal universally approved by traffic authorities; to provide a direction indicator which can be so disposed that no portion of the mechanism projects beyond the side frame of the windshield or the body of the car, and to provide means whereby the directional setting may be done with one operation and the projecting and retracting of the signal may be done by another.

The invention consists of a horizontal tubular member enclosing a signalling element capable of being projected beyond the member and expanded subsequent to projection, and means for supporting the signal in selective position to indicate "right" or "left" turns or "stop", as will be more fully described in the following specification and shown in the accompanying drawings, in which:

Fig. 1 is a general view of the invention as viewed from the rear.

Fig. 2 is a detail view of the signalling element.

Fig. 3 is a sectional view of the control mechanism as seen from the underside.

Fig. 4 is a sectional view taken on the line 4-4 of Figure 3.

Fig. 5 is a fragmentary view showing the disposition of the parts when the signal is set for a "left" turn.

Fig. 6 is a fragmentary view showing the disposition of the parts when the signal is set for a "stop".

Fig. 7 is a fragmentary view showing the disposition of the parts when the signal is set for a "right" turn.

In the drawings like characters of reference indicate corresponding parts in each figure.

The numeral 1 indicates generally a tubular member which is adapted to be set above the windshield of a car having a left hand drive and under the sun visor and to extend to the left to a point substantially parallel with the left post of the shield. This tubular member is open at the left extremity and closed at the right extremity and is fitted intermediate its length with a T generally indicated by the numeral 2. The tubular member 1 is divided by said T into parts 3 and 4, the part 3 normally enclosing a signalling element generally indicated by the numeral 5. A rectangular tubular body 6 is endwise slideable, but non-rotatably mounted within the outer end of the part 3 of the tubular member 1, which tubular body 6 is provided with side wall extensions 7 between the upper extremities of which a pivot pin 8 is placed to swingingly support the signalling element. The signalling element is formed with a pair of side plates 9 suitably spaced apart and provided with upper and lower longitudinal slots 10. Pivotedly mounted at the outer ends of the side plates 9 are two blades 11, which are mounted on the outer faces of the plates 9 and are each pivotally connected adjacent their outer edges and their rear extremities to a spreader 12 which in turn is pivotally connected by a pin 13 to a push rod 14 slidably mounted within the tubular body 6. The pins 13 of the two spreaders 12 extend through the slots 10 in the side plates 9, which serve as guides therefor.

It will be noticed that the pivotal points at opposite ends of the spreaders 12 are disposed on opposite sides of the longitudinal centres so that an inward pull on the pull rod 14 will cause the outer ends of the spreaders to swing outwardly and dispose the blades 11 and themselves in the form of an arrow head, thus producing when so disposed a signalling element when displayed of much greater area than when it is confined within the tubular member 1.

A substantially triangular tumbler 15 having a trigger 16 is rockingly mounted upon a pin 17 and carried between the side plates 9, attached to the tumbler by a pin 18 is the pull rod 14. The tumbler is resiliently retained in either of its two stationary positions by a suitably supported leaf spring 19. The trigger 16 is normally held in contact with the lower side wall of the part 3 of the tubular member 1, which adjacent its outer end is slotted as at 20 so that as the tumbler 15, carried by the side plates 9, is moved outwardly the trigger will drop into the slot 20 and be engaged by the tube as it reaches the outer end of said slot, thus rocking the tumbler into the position shown in Figure 2 and spreading the signalling element into display form as shown therein.

Secured to the inner end of the tubular body 6 is a bar 21 which extends beyond the T 2 and into the part 4 of the tubular member. Adjacent the inner end of the bar 21 a latch 22 is formed, see Figures 5, 6, and 7, which serves to limit the outer travel of the signalling element as will be hereinafter described. Hingingly connected to the lower inner edge of the side plates 9 is a cranked link 23 having a vertical dimension substantially equal to the vertical diameter of the tubular member part 3, which is connected at its inner end to a light rod 24, the rod in turn being connected to a tension spring 25 anchored in the part 4 of the tubular member 1 to withdraw the signalling element into the tube.

The rod 24 is partly cut away to provide two gaps 26 and 27 respectively which gaps are disposed towards the angular leg of the T 2. A cord 28 is attached to the inner end of the rod 24 and extends along the part 4 of the member 1 around a small sheave 29 and outwards through a guide 30 and is fitted with a suitable knob, not shown, for convenience in pulling. The guide 30 is mounted upon a plate 31 hinged as at 32 to a flanged cover 33 fitted upon the T and is capable of being moved to the dotted line position shown in Figure 3, when the cord 28 is drawn to the left. Journalled concentrically in the flanged cover 33 is a horizontal shaft 34 fitted with a lever 35 having a flange 36, which latter is held in contact with the hinged plate 31 by a spring 37 mounted on the shaft and tending to force it inwards into the T. The inner end of the shaft 34 is offset to form a crank 38 capable of being moved by the lever 35 into the three positions shown in Figures 5, 6 and 7. On the end of the crank 38 a disc 39 is fitted, which is concentric with the shaft 34 and is journalled in a step bearing 40 at the base of the T, the diameter of the disc is equal to the length of the gap 27 of the rod 24, so that the disc may be urged into the gap as the rod is moved endwise to bring these elements into register. The outer face

of the disc is provided with a pair of aligned radial grooves 41 which define at their inner ends a central stop 42 shown in dotted line in Figures 5, 6, and 7 which is of a diameter equal to the gap 26 in the rod 24, so as to be capable of entering said gap to hold the rod against endwise movement. Extending from the step bearing 40 is a pair of guides 43 in which the inner end of the bar 21 is slidably mounted.

As the signalling element when indicating a stop as shown in Figure 6 assumes its angular position by gravity, it is desirable to limit its downward movement, I therefore provide a stop 44 on the lower edge of the side plates 9 which engage the side wall extensions 7.

Having thus described the several parts of my invention I will now briefly explain its operation.

When a left turn is to be made the lever 35 is turned in an anti-clockwise direction, thus disposing the aligned grooves 41 of the disc 39 in alignment with the rod 24 and the cord 28 is pulled in a downward direction, thus moving the rod 24 to the left as shown in Figure 5 until the stop 42 is forced by the spring 37 into the gap 26 of said rod. The endwise movement of the rod in this action is less than when displaying signals indicating stop or right turn and is insufficient to project any portion of the triangular link 23 beyond the outer end of part 3 of the tubular member 1, so that the link is unable to move about its longitudinal axis and the signalling element 5 is projected horizontally outward a sufficient distance only to permit the trigger 16 to be swung over to the position shown in Figure 2 and the signalling element to be expanded as shown therein. If a signal is to be given indicating a "stop", the lever 35 is set in a vertical position, see Figure 6, thereby setting the aligned grooves 41 at an angle to the rod 24 so that the face of the disc bears against the side of the rod until, on its being moved in response to pulling the cord, the gap 27 comes into register with the disc, which latter is forced into said gap by the spring 37.

The endwise movement of the rod for this signal is greater than that first described, and after the signalling element has been expanded permits a portion of the triangular link 23 to project beyond the outer end of part 3 of the tubular member 1, so that the preponderance of weight of the outer extremity of the signalling element will cause it to rock and point downwards as shown in Figure 6, and in so doing raise the outer end of the link 23 above the upper level of the tubular member. In this case it will be noticed that the latch 22 of the bar 21 is drawn to the left beyond the crank 38.

If a signal indicating a turn to the right is to be made, the lever 35 is turned in a clockwise direction and the crank 38 is in conse-

quence moved to the left of its axis of rotation and in line with the path of travel of the latch 22 of the bar 21, so that when the rod 24 is drawn to the left by means of the cord, 5 the latch 22 on reaching and engaging the crank 38 arrests the bar and the tubular body 6 at the point shown in Figure 7 and as the rod 24 continues its movement and in view of the thrust through the triangular link being be-

10 low the pivotal point about which the signalling element is swung, the said element will be swung to point diagonally upwards until the gap 27 of the rod 24 becomes engaged by the disc 39 and holds the element against 15 further upward movement.

The restoration of the signalling element to normal or retracted position is the same in all cases, and simply requires the cord 28 to be tensioned and drawn to the left to swing 20 the plate 31 about its hinge pin 32 by drawing the guide 30 to one side. The plate in swinging away from the flanged cover 33 draws the shaft 34 outwardly against the action of the spring 37 and removes the disc 25 39 from the gap in the rod 24, thus allowing the spring 25 to withdraw the rod 24 and the signalling element to the right as the tension on the cord 28 is slackened.

What I claim as my invention is:

30 1. A direction indicator for motor cars comprising a guide, a signalling element normally housed in the guide consisting of a carrier pivotally supporting a display member, a cord operatively connected to the display member capable of moving the signalling element into display position beyond the guide, a member for limiting the outward movement of the carrier and the display member whereby on the tensioning of the cord the carrier 35 will be brought to rest and the display member will be upwardly inclined and for retaining the member in adjusted position, spring means for withdrawing the signalling element into normal position, and means as the 40 cord is drawn to one side for releasing the signalling element and permitting it to be withdrawn into normal position.

45 2. A direction indicator for motor cars comprising a guide, a signalling element normally housed in the guide consisting of a carrier pivotally supporting a display member, a cord for moving the signalling element to project the display member beyond the guide and for selectively moving said member about 50 its pivot, separate means for controlling the pivotal movement of the display member adapted to be set prior to the outward movement of the signalling element, and means for returning the signalling element to normal 55 position within the guide.

60 3. A direction indicator for motor cars comprising a guide, a signalling element normally housed within the guide consisting of a carrier pivotally supporting a display member and a rod connected to said display mem-

ber, means for selectively limiting the outward movement of the carrier and the rod, manual means for moving said carrier and rod in an outward direction, means for retaining said carrier and rod at the limit of their outward movement, and means for releasing the retaining means whereby the signalling element is returned to normal position within the guide. 70

Dated at Vancouver, B. C., this 19th day 75 of January, 1931.
